US00D485759S

(12) **United States Design Patent** (10) Patent No.: **US D485,759 S**
 Janky et al. (45) Date of Patent: ** Jan. 27, 2004

(54) **FLIP LID**

(75) Inventors: **Gregory T. Janky**, Sammamish, WA (US); **Peter G. Nazaroff**, Seattle, WA (US); **B. Cameron Smith**, Seattle, WA (US); **Blake Stancik**, Mukilteo, WA (US); **Scott Thielman**, Seattle, WA (US)

(73) Assignee: **Pacific Market, Inc.**, Seattle, WA (US)

(**) Term: **14 Years**

(21) Appl. No.: **29/174,060**

(22) Filed: **Jan. 8, 2003**

(51) LOC (7) Cl. **09-07**

(52) U.S. Cl. **D9/449**; D9/447; D9/435; D7/392.1; D7/900

(58) **Field of Search** D7/392.1, 900, D7/391, 392, 601, 602, 608, 538, 541, 542, 510, 511, 396.2, 612, 321, 313; D9/449, 447, 435, 503, 440, 445, 446; 220/711, 254, 713
